Dr. T. Mallory, his Atty.

United States Patent Office.

MARVIN CONVERSE, OF JORDAN, NEW YORK.

Letters Patent No. 65,058, dated May 28, 1867.

IMPROVED CURTAIN FIXTURE.

The Schedule referred to in these Letters Patent and making part of the same.

TO ALL WHOM IT MAY CONCERN:

Be it known that I, MARVIN CONVERSE, of Jordan, in the county of Onondaga, and State of New York, have invented a new and useful improvement in the Mode of Hanging Window-Curtains; and I do hereby declare that the following is a full, clear, and exact description of the same, reference being had to the annexed drawings, making part of this specification, in which—

Figure 1 is an elevation, and

Figure 2 is a vertical section.

The same letters are used in both figures in indicating similar parts.

My improvement consists in attaching the curtains of a window to a sliding strip, which may be moved up and down upon rods placed on each side of the window-frame by an arrangement of cords to be hereafter explained, so that light and air may be admitted through the window over the top of the curtain.

A is the casing of a window, in which, on each side of the upper part of the window, I place vertical parallel rods B B, to which the strip C, crossing the window, is attached by four eyes, C', so that the strip may be moved freely up and down between the casing and the rods. The curtain D is attached to the movable strip C, operating upon a roller or in other convenient and ordinary manner. The strip is suspended upon two cords, E and E', which, hanging down the side of the casing, are carried through the eyes F, from which the cord E is carried down and attached to the end of the sliding strip C on that side of the window, and the cord E' is carried horizontally over the window, and passing through the eye F' is carried down and attached to the other end of the sliding strip C. The cords are of such length that the sliding strip C shall be maintained in a horizontal position as it is raised or lowered. The cords E and E' should unite below the point where they are carried through the eye F, leaving them separated as far as may be necessary to permit the sliding strip to descend to the lower end of the rods B B. Instead of the eyes F F' pulleys may be used to advantage. Instead of placing the rods B B on the front of the window-frame, as shown, they may be attached to the opposite faces of the frame, near the sash, and in such case the sliding strip C, to which the curtain is attached, would be shortened so as to slide between the rods, to which it would be in that case attached by means of eyes C' C' placed in the ends of the strip. In that case the ends of the sliding strip C might be made to slide in slots in the sides of the casing or between cleats attached thereto instead of sliding on vertical rods B, as described. If the ways should be employed, then the piece C might be dispensed with and the ends of the roller to which the curtain is attached be inserted in sliding blocks placed in said slots, to which the cords may be attached.

What I claim as my invention, and desire to secure by Letters Patent, is—

The sliding frame C, carrying the curtain-roller and journals, moving freely upon the edge of the window-frame, on the guide-rods B, in combination with the cords A, E', and D', for raising and lowering the curtain, substantially as described.

In testimony whereof I have signed my name to this specification in the presence of two subscribing witnesses.

MARVIN CONVERSE.
